CONSTRUCTION ROLL SCREEN UNWINDER AND STRAIGHTENER

Rene A. Leroy, Rockford, Ill.

Application October 15, 1951, Serial No. 251,313

2 Claims. (Cl. 153—88)

This invention relates to a construction roll screen unwinder and straightener, designed to expedite the unwinding and cutting to lengths of such heavy screen material, and, what is more important, eliminate the hazards of serious injury commonly associated with doing such work the old way, besides making the material straight so that it is ready for use and can be handled and worked with more readily.

The principal object of my invention is to provide an elongated frame having on its one end portion upright supports to carry the shaft supporting the roll of wire screen and having intermediate its ends higher uprights supporting a roller of small radius at a predetermined elevation above the roll of screen material, over which the screen is adapted to be pulled in unwinding the screen from the underside of the roll, so that the screen is given a reverse crimp sufficient to straighten it and cause it to lie flat on the ground. The screen, when straightened in this way can be cut safely, there being no longer any danger of a loose cut end springing upwardly and putting out an eye or doing other serious injury to a workman. Such injuries were very common when this material was handled the old way, which consisted in merely rolling the roll to unwind a given length lying on the ground and then cutting off the length thus unwound. The spring-back in the unstraightened material, taken together with the sharpness of the freshly cut ends on the wires, made a treacherous combination hard to cope with.

Another object is to provide on the frame between the crimping roller and the screen roll supports a guard or bumper overlying that portion of the screen extending between the roll and the crimping roller which will serve to retain the cut end portion of the wire screen if the loose end portion tends to spring upwardly when threading it through the rig, or when a straightened end portion is cut off next to the crimping roll. Transversely extending supports are also provided between the roll and crimping roller to engage the loose end portion of the screen from below so as to prevent downward buckling and retain the end portion between the guard or bumper and the transverse support.

Another object is to provide power operated sprocket means in conjunction with an annularly grooved supporting roller on the outgoing end of the frame at the required elevation below the level of the crimping roller to pull the screen material off the roll and over the crimping roller and give it a uniform crimp, the sprockets having cogs spaced to fit the mesh of the screen. Construction wire screen is commonly made in a 6-inch mesh, so that the one sprocket means will fit all materials to be unwound and straightened.

Still another object is to provide on the outgoing end of the frame suitable shears for cutting off the material each time a specified length has been unwound.

The invention is illustrated in the accompanying drawings, in which—

Fig. 1 is a side view of the unwinding and straightening

2

rig made in accordance with my invention, illustrating the mode of operation;

Fig. 2 is a top view;

Fig. 3 is a cross-section on the line 3—3 of Fig. 1 showing the power operable unwinding means; and

Fig. 4 is an end view showing the cut-off shears.

The same reference numerals are applied to corresponding parts throughout the views.

The elongated frame of the rig is designated generally by the reference numeral 4 and may be of any suitable or preferred construction, providing a pair of spaced uprights 5 on the one end portion, in the upper ends of which bearing recesses 6 are provided. The shaft 7 received in these bearings extends through the center of the roll 8 of construction wire screen, this being of the kind made of rather heavy wire suitable for use in reinforced concrete construction work in buildings and elsewhere. A loading platform 9 of any suitable construction is provided on the same end of the frame 4 terminating in spaced relation to the bearing recesses 6, as shown in Fig. 2, so that the rolls of screen material can be lifted by means of a suitable hoist onto the platform 9 and rolled into place in the rig for unwinding and straightening, the shaft 7 finally rolling or sliding at its ends along the elevated side portions 9' of the platform until dropping into the bearing recesses 6. The uprights 5 have their upper end portions fastened to the extending side portions 9' of the platform 9, as indicated at 10, thus lending rigidity to these uprights and reinforcing the same so that they are adapted to carry the heavy loads which these rolls represent. Braces 11 are suitably provided on the other side of the uprights to further insure the needed strength and rigidity and to assume the side-thrust imposed on the uprights 5 when the wire screen material is pulled in the direction of these braces in unwinding the material from the roll. Another pair of uprights 12 is provided intermediate the ends of the frame 4, and these uprights carry a shaft 13 on which a crimping roller 14 is mounted. The latter is of small radius and disposed at such an elevation with respect to the roll 8 of wire screen material that when the screen S is run over the roller in unwinding from the bottom of the roll 8, in the manner clearly illustrated in Fig. 1, the wire is given a reverse crimp sufficient to straighten it so that it will lie flat and will not tend to curl up when a certain length of the screen S is unwound and crimped is cut off. That eliminates most of the hazard that was formerly connected with unwinding and cutting such material to specified lengths. In some cases, where a low cost rig is desired, the free end of the screen S extended over crimping roller 14 may be simply attached to a truck or tractor and pulled to unwind the screen from the roll 8 and crimp it at the same time. However, as will soon appear, I prefer to provide power operated sprocket means indicated at 15 to pull the material from the roll 8 and over the crimping roller 14, because in that way a more uniform crimping action is assured. With that arrangement the screen, as it is unwound, is preferably also directed out over a table 16 between a pair of shear blades 17 and 18, which can be operated in any suitable way, as by means of a foot treadle 19, to cut off an unwound length.

A guard or bumper structure is indicated generally by the reference numeral 20 overlying the flight 21 of wire screen S extending from the roll 8 to and over the crimping roller 14. This guard structure is needed most in a rig having no power operated unwinder, because it is intended to prevent the unstraightened length of material represented in the flight 21 from springing upwardly when the screen happens to be cut off not far beyond the roller 14. To further confine such a loose end portion and prevent its dropping down to the bottom of the frame and coming off the crimping roller 14,

another roller 22 is provided on a shaft 23 parallel to and between the roller 14 and roll 8, and below but fairly close to the guard or bumper structure 20. In that way, when a loose end portion tends to spring upwardly and strikes the guard or bumper structure 16, the roller 22 engages the loose end portion of the wire screen from below and supports it against buckling downwardly too far away from structure 20, so that there will surely be enough length left projecting beyond the roller 14 to take hold of for the next pull, thereby speeding up the work considerably. The guard or bumper structure 20 may be of any suitable or preferred construction, the one shown consisting of a pair of longitudinally extending bars 24 fastened together intermediate their ends by a cross-piece 25 and fastened together at one end by another cross-piece 26, which is supported on brackets 27 projecting from the uprights 5. Another cross-piece 28 has the other ends of the bars 24 fastened thereto and is fastened to the uprights 12. The bars 24 extend beyond the cross-piece 26, as indicated at 29, and are curved upwardly and in an arc over and spaced from the roll 8, as indicated at 30, to serve as skids on which the wire screen material can slide if the roll 8 at the end of an unwinding operation should tend to loosen and expand to a larger radius due to the springback inherent in the rolled up material. These curved end portions 30, in other words, will serve to limit such loosening up of the wire screen material in the roll, without, however, interfering with the subsequent unwinding. It is also contemplated that sliders or shoes may be provided either on the uprights 6 or on the end portions 30 of the bars 24 to ride on the periphery of the roll 8, as indicated at 31, to maintain a certain amount of drag on the turning of the roll 8 and in that way further insure a more uniform crimping action at the roller 14. The shoes 31 can be pivoted, as at 32, and spring actuated, as indicated at 33, to maintain contact with the roll throughout the unwinding operation, as the roll, of course, decreases in radius. Side-thrust on the uprights 12 incident to pulling the screen material S over the roller 14 is assumed to some extent by braces 34, and these uprights are further reinforced by the framework 35 that is attached to and extends from the other side thereof and is attached to the frame 4 for support of the roller 22.

A pair of spaced uprights 36 provide bearing supports for the ends of a shaft 37 on which a plurality of spaced rollers 38 are welded or otherwise suitably secured for support of the screen material S while it is being unwound. Sprockets 40 operate in the spaces 39 between these rollers, the sprockets being secured on a shaft 41 received in other bearings provided therefor in the uprights 36. V-belt pulleys 42 are mounted on the projecting end portion of the shaft 41 to drive the same at a reduced speed in relation to the speed of a drive motor or engine and in a counterclockwise direction, as viewed in Fig. 1. The cogs 43 on the sprockets 40 are spaced approximately 6 inches apart so as to mesh nicely with the wire screen, construction wire screen being commonly available in 6-inch mesh. It is apparent, therefore, that with this power unwinding means the screen can be unwound with far less trouble and in much less time than where a truck or tractor is used. It is also evident that because the flight 44 of the screen material S is maintained uniformly at the downward angle shown relative to crimping roller 14, and because the unwinding by power operated sprockets 40 is certain to be at a more uniform rate and under more uniform tension, a more uniform crimping action is insured.

The screen material S is directed from the power unwinding means out over a table 16 so that all that is necessary is for a workman to conduct the outer end away from the rig as the material is unwound. Then,

when a desired length has been unwound, the movable shear blade 18 can be operated by pressing the treadle 19, after the motor or engine driving the unwinding means has been stopped. The blade 18 is suitably guided at its ends, as indicated at 45, and has a lever 46 which is pivoted at one end, as at 47, and pivotally connected thereto immediate the ends thereof, as indicated at 48, whereby to obtain the desired leverage. Further leverage is obtained by pivotally connecting, as at 49, a link 50 to the free end of the lever 46 and pivotally connecting the lower end of the link 50, as at 51, to an intermediate portion of the treadle 19, the latter being pivoted at its inner end, as at 52, to the frame 4.

15 The cut-off shears may be of a rotary crank-operated type in lieu of the type shown, the cranks or eccentrics on the rotary shaft having pitmans operated thereby and attached to the vertically reciprocable shear blade. The rotary shaft may be turned by a hand crank or by power, using a single revolution clutch, as only one reciprocation of the shear blade is needed. Also, in lieu of a continuous shear blade, I may use a plurality of V-shaped blades, locating such blades in laterally spaced relationship on a holder in the same spacing as the longitudinally extending wires of the screen to be cut, so that these wires will all be severed in the same stroke. Separate blades can be replaced, as required.

20 Another feature that may be incorporated easily is a counter operated with the sprocket shaft, so that one may readily measure out any given length of material from the roll by taking the readings off the counter. The cogs on the sprockets are six inches apart, as stated before, and, hence, each turn of the sprockets accounts for a definite known length of the material, which makes this method of measuring the material as it is unwound feasible.

25 In conclusion, while the present rig is best adapted for the use mentioned, it should be evident that it may be used for unwinding and straightening other rolled metallic material of a similar kind, like wire fencing, for example.

30 It is believed the foregoing description conveys a good understanding of the objects and advantages of my invention. The appended claims have been drawn to cover all legitimate modifications and adaptations.

35 I claim:

1. A device for unwinding from a roll and simultaneously straightening construction wire screen wound in a roll, said device comprising an elongated frame, bearings on one end portion thereof on which is supported a shaft carrying a roll of said screen to be unwound and straightened, the screen unwinding off the roll inwardly relative to the frame, a crimp member of small diameter in relation to the roll of screen material supported transversely of the frame in a predetermined elevated and appreciably inwardly spaced relation to the roll over which the screen in the unwinding thereof is extended upwardly on a substantially straight line substantially tangent to both the roll and crimp member and then downwardly from said crimp member at a small angle so that there is a predetermined included angle of crimp between the incoming and outgoing screen at said crimp member, means exerting a pull on the screen from its free end so that it passes over the crimp member under tension, and means for placing a predetermined drag on the turning of the roll so as to maintain a predetermined tension in the screen as it passes over the crimp member, whereby to straighten the screen, said crimp member comprising a roller rotatably mounted so as to afford rolling friction in the crimping operation and accordingly reduce the amount of pull necessary in unwinding and straightening the screen material, while also insuring substantially equal tension on the material on opposite sides of the crimp member, the device including an elongated guard extending from the vicinity of the roll to the vicinity of the crimp

member over and in closely spaced relation to the flight of screen material unwinding from the roll and passing over the crimp member to prevent accidental kickup of the free end when an unwound length is cut off.

2. A device for unwinding from a roll and simultaneously straightening construction wire screen wound in a roll, said device comprising an elongated frame, bearings on one end portion thereof on which is supported a shaft carrying a roll of said screen to be unwound and straightened, the screen unwinding off the roll inwardly relative to the frame, a crimp member of small diameter in relation to the roll of screen material supported transversely of the frame in a predetermined elevated and appreciably inwardly spaced relation to the roll over which the screen in the unwinding thereof is extended upwardly on a substantially straight line substantially tangent to both the roll and crimp member and then downwardly from said crimp member at a small angle so that there is a predetermined included angle of crimp between the incoming and outgoing screen at said crimp member, means exerting a pull on the screen from its free end so that it passes over the crimp member under tension, and means for placing a predetermined drag on the turning of the roll so as to maintain a predetermined tension in the screen as it passes over the crimp member, whereby to straighten the screen, said crimp member comprising a roller rotatably mounted so as to afford rolling friction in

the crimping operation and accordingly reduce the amount of pull necessary in unwinding and straightening the screen material, while also insuring substantially equal tension on the material on opposite sides of the crimp member, the device including an elongated guard extending from the vicinity of the roll to the vicinity of the crimp member over and in closely spaced relation to the flight of screen material unwinding from the roll and passing over the crimp member to prevent accidental kickup of the free end when an unwound length is cut off, and a secondary guard spaced closely below the same flight of screen material preventing downward displacement of said free end.
